ATTORNEY

UNITED STATES PATENT OFFICE

EDWARD J. BARANY, OF NEW YORK, N. Y.

GOLF GAME

Application filed December 5, 1927, Serial No. 237,699. Renewed January 7, 1930.

Ths invention has for its object the provision of a novel golf game.

A particular feature of the invention is the provision of a game in which the balls 5 are driven by means of a spring-controlled club end which is operated by a trigger. This arrangement permits a very close control over the amount of force applied to the ball and thereby introduces skill and variety into 10 the game.

The game is played upon a board suitably covered, preferably with a material such as felt, to simulate the turf of a golf course, and the invention includes the use of eyelets to 15 serve as driving tees and securing means for the covering.

Another feature of the invention resides in the structure of the balls, which are of some heavy material such as lead, and have a number 20 of flat or irregular facets. This construction prevents excessive rolling of the ball on the relatively small board representing the golf course.

In the drawings:
25 Fig. 1 is a plan view of the board used for the game.

Fig. 2 is an elevation of the golf club used.
Fig. 3 is a section through the club showing 30 the parts in a different position.

Fig. 4 is a section on line 4—4 of Fig. 1.
Fig. 5 is a section on line 5—5 of Fig. 1.

Fig. 6 is an elevation of marking flags that are used with the game.
35 Fig. 7 is a plan view of the ball used with the game.

Referring to the drawings more particularly, the game board comprises a base 10 which is covered by felt or other suitable material as at 11. A guard strip 12 surrounds 40 the board and holds down the edges of the covering 11. The board may be formed with any desired bunkers and traps as at 13.

Sunken cups 14 form the "holes" for the game, and a rim 15 surrounds each hole in 45 order to add to the difficulty of sending the ball into the hole. A numeral may be displayed on the bottom of each hole as shown in Fig. 1, and a socket 16 at the bottom of each cup provides means for holding the flags 17 in the well-known manner of out-door golf.

The tee for each hole comprises a tubular rivet 18 which passes through the base 10 and holds a square washer 19 down against the covering 11.

The ball is formed of lead or other suitable 55 heavy material and has its surface formed with a plurality of facets 20 to retard the rolling movement of the ball.

The novel golf club, as clearly shown in Figs. 2 and 3, is formed with a forked lower 60 end in which is pivoted the striking portion 21 having a head 27 resembling that of a conventional golf club. A spring 22 presses against the striking portion and normally holds it in the straight position of Fig. 2. 65 A pivoted trigger 23 has an exposed portion 24 and a projection 25 which engages behind the end 26 of the striking portion.

The game is played in the following manner:
70

The ball is placed on the first tee and the club is held in an upright position touching the ball. The trigger part 24 is then pressed to draw back the striking portion 21, and upon releasing the trigger the spring drives 75 the striking portion 21 forward to strike the ball. The amount of drawback can be regulated by the amount the trigger is depressed and by varying the vertical angle of the club the amount of lift imparted to the ball can be 80 varied. In this way the game can be played with as much skill as out-door golf and provides a very interesting pastime.

I claim:

A playing stick for a golf game comprising 85 a handle, a forked lower portion carried by the handle, a striking portion pivoted in the forked portion, a spring carried by the handle and engaging the striking portion, and a trigger pivoted in the forked portion 90 and adapted to engage the striking portion.

In testimony whereof I affix my signature.
EDWARD J. BARANY.
